COMBINED CONTAINER AND CLOSURE
THEREFOR

William H. Robinson, 602 E. Jefferson St.,
Miamisburg, Ohio

Filed Nov. 28, 1958, Ser. No. 53,578

Term of patent 14 years

(Cl. D58—12)

Figure 1 is a side elevational view of a combined container and closure therefor embodying my new design and showing the closure raised from the container;

I claim:

The ornamental design for a combined container and closure therefor, as shown.
